UNITED STATES PATENT OFFICE.

ROBERT TAYLOR AND ROBERT DICKSON LAWRIE, OF PHILADELPHIA,
PENNSYLVANIA.

DESIGN FOR FORKS, SPOONS, &c.

Specification forming part of Design No. 512, dated October 19, 1852.

To all whom it may concern:

Be it known that we, ROBERT TAYLOR and ROBERT DICKSON LAWRIE, of the city of Philadelphia, in the county of Philadelphia and State of Pennsylvania, have invented or produced a new and original Design for Ornamenting the Handles of Spoons, Forks, Ladles, Sugar-Tongs, and Knives in any of the metals now in use or which may be brought into use hereafter; and we do hereby declare that the following is a full and exact description of the same.

The design is a shield with scroll ornaments on the front side and upper end, surrounded by raised beads, which beads form a finish on the outline or sides of the handle, terminating at the breast or curve with a scroll. On the reverse or back the upper end is orna-

mented with a plain scroll and the entire outline or edge finished with raised beads, same as front side, only terminating at the heel with an ornamental scroll.

We do not claim the outline of the spoon, fork, ladle, &c.; but

What we do claim, and desire to secure by Letters Patent, is—

The design and configuration of the ornaments for spoons, forks, ladles, knives, sugar-tongs, &c., above described, and set forth in the accompanying drawing.

ROBT. TAYLOR.
ROBERT DICKSON LAWRIE.
